UNITED STATES PATENT OFFICE

MACK T. HOLLOWAY, OF GRAYMONT, GEORGIA

TWO-CYCLE GAS ENGINE

Application filed May 7, 1930. Serial No. 450,472.

This invention relates to that type of two-cylinder two-cycle engine in which a pump is arranged to supply directly to the cylinders the charges of explosive mixture for scavenging and power, and the object of the present invention is to simplify the construction in such manner as to do away with all valves between the pump and the power cylinders, as more fully hereafter set forth.

10 In the drawings annexed:

Figure 1 is a view partially in plan and in horizontal section, and

Figures 2, 3 and 4 are schematic views showing the pistons in various positions.

15 Referring to the drawings by reference characters, 5 designates one of the power cylinders and 6 the other power cylinder, and 7 designates the pump cylinder. The usual power pistons 8 work in the power cylinders and are connected to the main or crank shaft 9 by the usual piston rods 10. A solid piston 11 works in the pump cylinder and is connected by a rod 12 to a crank on the pump shaft 13, this shaft 13 being geared 20 to the crank shaft, by gears 14 and 15 at a two-to-one ratio, so that with each revolution of the crank shaft, the pump piston will receive two reciprocations.

The cylinders 5 and 6 are provided with the 30 usual exhaust ports 16 and the usual inlet ports 17, these ports in each cylinder being arranged as usual opposite each other and about mid-length of the cylinder. Each of the inlet ports 17 is connected by a conduit 35 18 with a port 19 in the top of the pump cylinder, at a point beyond the extreme top stroke of the pump piston, so that the ports 19 will always be in communication with the ports 17. Each power cylinder is provided 40 with the usual spark plug 20, and the inlet port 21 in the top wall of the pump cylinder is connected to a carburetor 22 of any usual construction, this carburetor being provided with a check valve 23, which is adapted 45 to open inwardly.

The operation of an engine thus constructed will be obvious from a study of the three diagrams. Each downward stroke of the pump piston draws in a charge of carbureted air through valve 23, and each up-stroke of the piston forces the charge thus drawn in into one or the other of the power cylinders without compressing the charge. In Figure 2, the piston in power cylinder 5 is compressing and its piston has closed port 17 as well as 55 port 16; the pump piston is drawing a charge into its cylinder through the carburetor, the port 17 at the other side being closed by the other power piston, this latter piston being in the act of making a working stroke. At 60 about the time the right hand power piston descends far enough to uncover the ports 16, 17, the pump piston will have started upwardly to thus perform the scavenging operation for power cylinder 6 and follow in the 65 usual manner by charging the same, preparatory to the upward, compression stroke of the power piston in said power cylinder 6. Keeping in mind that the pump piston makes two strokes for each revolution of the crank 70 shaft, it will be observed that the foregoing cycle of operations is carried out in each power cylinder. With my arrangement, it will be seen that I not only do away with the 75 necessity of using the crank casing as a compression chamber, but also do away with all valves between the pump cylinder and the power cylinders. And it will be further noted that I do not use the pump for compression purposes.

I claim:

An engine of the type set forth embodying a pair of two-cycle power cylinders having their pistons connected to a crank shaft and each being provided with a spark plug and 85 also with an inlet port and an outlet port, a pump cylinder having two exhaust ports in constant connection respectively to the inlet ports of said power cylinders, this pump cylinder being provided with an inlet for the 90

charge mixture, this inlet being provided with a valve adapted to open only on the suction stroke, a piston working in said pump cylinder, and means connecting said piston with the aforesaid crank shaft adapted to impart to the pump piston two reciprocations for each revolution of the crank shaft, the ports being so positioned and the movement of the pistons being so timed that on each suction stroke of the pump piston the power pistons will close their companion inlet ports and on each expelling stroke of the pump piston one or the other of said inlet ports will be opened and the other closed so that on each propelling stroke one or the other power cylinder will be successively scavenged and charged without compressing the charge.

In testimony whereof I hereunto affix my signature.
